UNITED STATES PATENT OFFICE.

ROLAND J. MARKHAM, OF SPOKANE, WASHINGTON.

DESIGN FOR A BODY FOR A FRETTED MUSICAL INSTRUMENT OR SIMILAR ARTICLE.

Application filed September 9, 1924. Serial No. 10,719. Term of patent 7 years.

To all whom it may concern:

Be it known that I, ROLAND J. MARKHAM, a citizen of the United States, residing at Spokane, in the county of Spokane and State of Washington, have invented a new, original, and ornamental Design for Body for Fretted Musical Instruments or Similar Articles, of which the following is a specification, reference being had to the accompanying drawing, forming part thereof.

Figure 1 is a front elevation of a body for a fretted musical instrument or similar article, showing my new design.

Figure 2 is a side elevation of the same.

I claim:

The ornamental design for a body for a fretted musical instrument or similar article, as shown.

ROLAND J. MARKHAM.
